DESIGN FOR A PRUNING SAW

George L. Whitman, Weedsport, and Carl D. Gunn, Auburn, N. Y.

Application February 12, 1947, Serial No. 136,874

Term of patent 14 years

(Cl. D93—4)

To all whom it may concern:

Be it known that we, George L. Whitman and Carl D. Gunn, citizens of the United States of America, and residents of Weedsport, in the county of Cayuga and State of New York, and Auburn, in the county of Cayuga and State of New York, respectively, have invented a new, original, and ornamental Design for a Pruning Saw, of which the following is a specification, reference being had to the accompanying drawing, forming part thereof.

In the drawing:

Figure 1 is a side elevation of the pruning saw, showing our new design;

Figure 2 is a bottom plan view of the saw, with the saw positioned as shown in Figure 1; and

Figure 3 is a top plan view of the saw, with the saw positioned as shown in Figure 1.

We claim:

The ornamental design for a pruning saw, substantially as shown.

GEORGE L. WHITMAN.
CARL D. GUNN.
